(Cl. D58—10)

To all whom it may concern:

Be it known that we, Ernest L. Du Pree and Daniel Goldstein, citizens of the United States of America, residing, respectively, at town of Weston, county of Fairfield, and State of Connecticut, and New York, N. Y., have invented a new, original, and ornamental Design for a Combined Bottle Stopper and Pourer, of which the following is a specification, reference being had to the accompanying drawing, forming part thereof.

Figure 1 is a front elevational view of a combined bottle stopper and pourer embodying our new design;

Figure 2 is a side elevational view thereof; and

Figure 3 is a top plan view of the same.

We claim:

The ornamental design for a combined bottle stopper and pourer, as shown,

ERNEST L. DU PREE.
DANIEL GOLDSTEIN.
